Harlan A. Hadley, Burlington, Vt., assignor to
H. A. Hadley Associates, Inc., Burlington, Vt., a
corporation of Vermont

Application July 12, 1949, Serial No. 3,851

Term of patent 14 years

(Cl. D52—10)

To all whom it may concern:

Be it known that I, Harlan A. Hadley, a citizen of the United States, residing at Burlington, in the county of Chittenden and State of Vermont, have invented a new, original, and ornamental Design for a Balance Scale, of which the following is a specification, reference being had to the accompanying drawing, forming part thereof.

In the accompanying drawing:

Fig. 1 is a front elevational view of a balance scale, embodying my new design,

Fig. 2 is a side elevational view thereof, and

Fig. 3 is a perspective view thereof with the indicator holder flexed out of straight-line position.

I claim:

The ornamental design for a balance scale as shown.

HARLAN A. HADLEY.
